(57) **CLAIM**

The ornamental design for a actuator housing for a flush
valve, as shown and described.

DESCRIPTION

FIG. 1 is a perspective view of my new design for an
actuator housing for a flush valve;

FIG. 2 is a left end elevation view thereof, the right end
being a mirror image of the left end;

FIG. 3 is a front elevation view thereof;

FIG. 4 is a rear elevation view thereof; and,

FIG. 5 is a top plan view thereof, the bottom view being a
mirror image of the top view.

The broken line showing of the flushometer housing in FIG.
1 is for illustrative purposes only and forms no part of the
claimed design.
